UNITED STATES PATENT OFFICE.

CHARLES LEA, OF BOSTON, MASSACHUSETTS, ASSIGNOR TO THE AUTOMATIC MERCHANTIZER, INC., OF BOSTON, MASSACHUSETTS, A CORPORATION OF DELAWARE.

COIN-CONTROLLED APPARATUS.

Application filed June 15, 1921. Serial No. 477,819.

My invention relates to coin-controlled apparatus, and to vending machines, and particularly but not exclusively to a coin-controlled vending machine for cans.

5 My invention will be best understood from the following description when read in the light of the accompanying drawings of a specific embodiment of my invention selected for illustrative purposes, while the scope 10 of my invention will be more particularly pointed out in the appended claims.

Referring to the drawings:

Fig. 1 shows in elevation the front of the submitted embodiment of my invention;

15 Fig. 2 is a view looking into the back of the machine when in opened position;

Fig. 3 is a perspective according to Fig. 2 of the lower portion of the machine;

20 Fig. 4 is a section on the line 4—4 of Fig. 1;

Fig. 5 is a section on the line 5—5 of Fig. 4;

Fig. 6 is a section on the line 6—6 of Fig. 5.

25 Referring to the drawings, I have shown a cabinet or other suitable reservoir, for receiving articles to be vended, which articles are indicated by the cans *a* although it will be understood of course that my in-

30 vention is not limited to the vending of cans. Herein the cabinet comprises a shallow box of sheet metal or other suitable material, and is of a depth approximately corresponding to the height of the cans. The cabinet 35 is supported by hinges 1, carried by the side wall 3 of the cabinet and secured to a plate 5, the latter being adapted to be fastened to a wall or other suitable supporting means.

When in operation the cabinet is swung 40 back against the plate 5 and held in position by means of the lock 7 and the cooperating keeper 9. The front face of the cabinet is provided with perforations 11 to render the contents of the cabinet visible,

45 while at the lowermost corner is provided an orifice 13 through which the cans may be moved when permitted to escape by the coin-controlled apparatus indicated in its entirety at 15.

50 The articles to be vended, hereinafter referred to as cans, are arranged in the cabinet in stacks, and as shown compartments for four such stacks are provided by means of the pairs of wires 17, these wires being 55 arranged vertically in spaced relation and

secured to the upper wall 19 of the box at their upper ends, and at their lower ends to the upper edges of the plates 21, the latter being secured to the front wall 23 of the cabinet. Below the plates is shown a strip 60 25 of width approximating the depth of the cabinet, which strip extends from the wall 3 downwardly to a point spaced from the opposite wall 27 of the cabinet. Below the strip 25 is shown a second strip 29 which 65 extends from the wall 27 to the bottom wall 31 of the cabinet at a point adjacent the orifice 13. The strips 25 and 29 afford a run-way for guiding the cans from the stacks to the orifice. 70

Herein for controlling the escape of the cans, is an arcuate shaped gate 33, of radius approximating that of the cans, the gate having the upper edge 34 and the lower edge 35, the latter normally adjacent the strip 29. 75 The normal position of the gate is as illustrated by Figs. 2 and 3, in which position, it will be noted, a can is received by the gate. When the gate is released by the coin-controlled mechanism, in a manner herein- 80 after described, and it is turned in the direction of the arrow shown by Fig. 2, the lower edge 35 of the gate will pass between the two lowermost cans and will permit the can received by the gate to roll down the incline 85 29, where it may be removed through the orifice 13. When the gate is moved back to the position shown by Figs. 2 and 3, a new can moves into the recess afforded by the gate and is in position to be discharged when 90 the gate is again operated.

95 Preferably I discharge the contents of one stack before starting to discharge the contents of the other stacks. Specifically in the submitted embodiment of my invention I discharge first all the cans of the stack at the extreme left hand side of Fig. 2, and the other stacks in order from left to right. As shown by Fig. 2, the first two stacks have been completely discharged, the third 100 stack has two cans remaining in it, while the fourth stack has been untouched. Herein for securing this result, I provide the members 37, 38 and 39 acting as gates and pivoted to the bottom edges of the plates 21. 105 These members may be formed in any suitable manner, and as shown consist of wires bent to form the side arms 41 provided with eyes 43 received in suitable perforations 45 in the plates 21 so as to permit the levers 110

thus formed to swing freely about the fulcrums afforded by the eyes. Each arm 41 is provided with an offset portion 47 adapted to engage the lowermost can of the stack 5 at the right of the lever as viewed by Fig. 2, while the cans at the left of the lever force the portion 47 against said lowermost can. It will be observed from Fig. 2 that the shoulder afforded by the offset portion 10 47 of the lever 39 engages the lowermost can of the right hand stack and that a can is resting upon the end of the lever. It will also be noticed that the offset portions 47 are close to the fulcrum of the lever so that 15 considerable leverage is exerted against the lowermost can in engagement with the offset portion. I have found by this arrangement that a single can is sufficient to hold the lever in position. Referring to Fig. 2, when 20 the last can is removed from the stack shown as undergoing the discharging operation, the lowermost can of the right hand stack will force the lever 39 upwardly to a position corresponding to that of the lever 38 25 to permit the cans in the right hand stack to discharge. The levers 38 and 39 are given an arcuate shape to guide the cans from the stack to the strip 25, and to insure that the can will always be in engagement 30 with the concave side of the lever at a point more remote from the fulcrum than the offset portion 47. The lower ends of the levers 38 and 39 are of less width than the distance between the eyes 43 in order that when the 35 levers are moved into their elevated position they will pass through the space between the side arms of the lever in front of them and to permit such movement the plates 21 are cut away to provide the recesses 40 49.

The apparatus for operating the gate 33 is adapted to be controlled by the insertion of coins, tokens, and the like of predetermined characteristics, which hereinafter will 45 be referred to as coins. Herein the apparatus comprises a casing 51 provided with an integral inwardly extending bearing member 52 which rotatably supports a spindle 53 carrying at its end exterior of the 50 casing the operating lever 55 and at its other end a boss 57 made integrally with the plate 59 carrying the gate 33. As shown, the coin-controlled apparatus is secured to the front wall 23 of the cabinet by means of 55 screws or other fastening members 61 engaging the flange 63 of the casing as shown in Figs. 4 and 5.

As shown, the plate 59 is provided with a flange 65 which, at the upper portion shown 60 in Figs. 4 and 5, is enlarged in height and thickness to provide a head 67 having the squared portions 69 acting as abutments for engaging the stops 71 carried by the casing 55, in order to determine the limit of movement of the gate. The normal position of

the parts is as shown by Fig. 5 in which position one of the abutments 69 is held resiliently in contact with the upper stop 71 by means of the torsion spring 73, the latter being secured at its inner end to the pin 75 70 carried by the bearing member 52, and at its outer end secured to the cam flange 77 hereinafter referred to, which flange is made integral with the plate 59.

As shown, the head 67 constitutes a coin-carrying member, and is provided with a slot 79 normally in alignment with a slot 81 in the casing 55, in order that a coin, indicated at *b*, may be inserted into said slot 79. The head is further shown as provided with a slot 83 which receives a slide 85 on which the lowermost portion of the edge of the coin *b* is adapted to rest. The slide is of a length sufficient to extend from the stop 71 to the end of the slot 79 in the normal position 85 of parts so that when a coin is inserted it is supported by the slide close to the inner edge thereof.

Herein, pivotally supported, at an intermediate portion thereof, on the post 87 carried by the casing, is a lever 89 having the portion 90 bent to lie parallel to the inner surface of the head 67 and having its upper end edge 91 normally spaced to the left of the slot 79 as viewed by Fig. 5. The post 87 as shown is in the form of a sleeve which receives the pivot 92 of the lever, the post being cut away to form a stop 93 which engages the lever to prevent it from contacting with the head 67. It will be noted by the construction just described a limited movement of the head 67 is permitted before the end of the slide engages the edge 91 of the lever.

Herein on the inner surface of the casing, 105 in line with the slot 81, I secure one end of a flexible plate 95, the plate being bent as shown by Fig. 5 to force the coin *b* radially inwardly through the slot when the coin is brought into engagement with the plate by rotation of the head 67. Preferably but not necessarily the extent the plate projects inwardly may be adjusted, and for this purpose I have shown the screw-pin 97 carried 110 by the casing and bearing against the outer side of the plate. After adjusting the plate, the end of the screw-threaded hole receiving the pin may be closed by the plug 99 to prevent tampering with the pin.

The operation of the parts of the coin-controlled apparatus so far described is as follows:—

Assume a coin *b* has been inserted through the slot 81 into the slot 79 and rests on the end of the slide 85. The operator then grasps the handle 55 and turns it in the direction of the arrow indicated in Fig. 5. This rotates the plate 59 and its head 67 to bring the end of the slide 85 against the end 91 of the lever 89. Continued movement 125

transfers the coin to the lever 89 and the upper edge of the coin being pressed by the plate 95 inwardly in a radial direction depresses the lever to permit the end 91 to disengage the slide 85, under which condition the lock afforded by the lever and slide is released and the operator is permitted to turn the head far enough to bring the left hand abutment 69 as viewed by Fig. 5 into engagement with the lower stop 71 which will permit a can to be discharged in the manner hereinbefore described. Release of the handle when the head has been moved to its final position will cause the spring 73 to return the parts to the initial position illustrated by Fig. 5. After the lock is released the coin slides along the upper surface of the lever and falls through the opening 101 of the lever to the bottom of the casing 20 where it falls through the chute 103 into the cabinet, being received therein under the strip 29. If the handle should be turned without first inserting a coin the head 67 will move to bring the end of the slide against the edge 91 of the lever and will continue to move until the end of the slide opposite that engaged by the lever moves against the wall of the casing to prevent further movement.

For insuring that the operator will move the gate to its final position after the lock is released I have shown the flange 65 with a series of recesses 105 adapted to be engaged by a pawl 107 pivoted on the end of a post 109 carried by the casing, said pawl having an oppositely extended portion 111 provided with an eye to which is attached the spring 113, the other end of the spring being attached to the end of the lever 89, so that both the lever and the pawl are normally biased to the position shown by Fig. 5 by means of the spring. At diametrically opposite points the flange 65 is cut away to provide openings 115 and 117. The extreme right hand recess 105 is positioned to be engaged by the pawl immediately upon release of the block, which action prevents return movement of the gate until the handle has been turned to cause the pawl to enter the cut-away portion 115 of the flange, the pawl entering the portion 115 when the lower stop 71 is engaged by the abutment 69 of the head.

It frequently happens that coins, slugs or the like of less than the predetermined size are inserted into the apparatus. Such coins when transferred by movement of the head to the lever 89 will not be of diameter great enough to cause the cam to move the coin inwardly far enough to disengage the lever 89 from the slide 85 and when the handle is released such coins will fall through the space between the end of the lever and the slide and be caught by a chute 119 provided for this purpose and opening through the

slot 121 on the face of the casing 55. Coins 65 discharged through the slot 121 will fall to the floor and it will be noted by these means that a signal is provided for calling to the attention of the custodian of the machine that improper coins are inserted.

For rendering ineffective inserted articles of magnetic material I herein provide a magnet 123 pivoted by means of a screw 125 to the projection 127 of the bearing member 52, said magnet having the two pole pieces 129 in close proximity to the slot 79 as shown by Figs. 4 and 5. The magnet is biased by means of the leaf spring 131 to cause it to bear against the edge of the cam flange 77 hereinbefore referred to, which flange causes 80 the magnet to swing about its pivot to draw the article into the dotted position of the coin 3 in Fig. 4 when the coin carrying member is moved through the limited travel permitted by the lock. This will cause the inserted article to either move off the slide or lever and be caught by the chute 119 and discharge through the slot 121, or when the carrier moves to return to its initial position to fall into the chute through the space between the end of the lever and the slide 83. It will be noticed by these means that I have, in addition to providing signalling means for calling to the attention of the custodian of the machine that coins, slugs and the like of less than predetermined size have been inserted, provided signalling means for those of magnetic material.

For rendering the discharging mechanism inoperative when the cabinet is empty I may employ a latch in the form of a lever 136 pivoted at 137 to the front wall of the cabinet and provided with a head 138, the latter affording a shoulder 139 which permanently engages the upper edge 34 of the gate 33 when the last can has been discharged. The opposite sides 140 and 141 of the head are respectively so shaped as to permit the upper edge 34 of the gate to lift the lever when a can is present and the gate is rotated and to permit a can moving into the recess afforded by the gate to lift the lever into its disengaged position as shown by Fig. 2. It will be noted that the shoulder 139 in the position shown by Fig. 2 is angularly spaced from the edge 34 so that when the shoulder engages said edge the gate will be positioned slightly clockwise of the position shown by Fig. 2. In the position shown by Fig. 2 the slot 81 of the casing and the slot 79 of the head 67 are in alignment and when the gate is in the position determined by engagement of the shoulder 139 with the edge 34 of the gate 110 these slots are out of alignment and thus 115 prevent the insertion of a coin.

The handle 55 I may secure to the spindle 53 in any suitable manner, but as shown I

have provided a friction joint between the two, in order to prevent forcible turning of the handle from injuring the mechanism of the coin-controlled apparatus. To this end 5 the lever herein is provided with a bore 132 which receives the end of the spindle and on either side of the bore extending therefrom lengthwise of the lever I form the slots 133. The slots render the central portion 10 of the lever flexible to permit the portions of the lever on opposite sides of the bore and slots to be clamped against the spindle by means of the screws 135.

Although I have described for purposes of 15 illustration one specific embodiment of my invention it is to be understood that wide deviations may be made therefrom without departing from the spirit of my invention.

Claims.

20 1. In a coin-controlled apparatus, a movable element, a member carried by said element and movable relatively thereto, a locking member for engaging said first mentioned member and permitting limited movement of said element, said first mentioned member being so constructed and disposed to receive an inserted coin and by such limited movement to transfer said coin to said locking member, means responsive to 25 said limited movement of said element for causing a coin of predetermined size to effect disengagement of said members, said limited movement of said element also operative to move said first mentioned member out of 30 coin retaining position when said member engages said locking member, and means for receiving and exposing coins which are ineffective to cause disengagement of said members.

40 2. Coin-controlled apparatus having, in combination, a movable element, locking means for said element comprising a locking member and a part for engaging said locking member, said part connected to said element for relative movement, means permitting limited movement of said part relative to said element to permit limited movement of said element when said part is engaged by said locking member, and means 45 rendered operative by the presence of a coin for causing said limited movement of said element to effect disengagement of said part and locking member.

50 3. Coin-controlled apparatus having, in combination, a movable element, locking means for said element comprising a locking member and a part for engaging said locking member, said part connected to said element for relative movement, means permitting limited movement of said part relative to said element to permit limited movement of said element when said part is engaged by said locking member, a cam, said element operative to move a coin into engagement with said cam for effecting disen-

gagement of said part and locking member upon said limited movement of said element.

4. In a coin-controlled apparatus, a movable element, a member carried by said element and movable relatively thereto, a locking member for engaging said first member and permitting limited movement of said element, said first member being so constructed and disposed to receive an inserted coin and by such limited movement to transfer said coin to said locking member, and cam means to cause said coin to release said locking member.

5. In a coin-controlled apparatus, a movable element, a member carried by said element and movable relatively thereto, a locking member for engaging said first member and permitting limited movement of said element, said first member being so constructed and disposed to receive an inserted coin and by such limited movement to transfer said coin to said locking member, and adjustable cam means to cause said coin to release said locking member.

6. In a coin-controlled apparatus, a movable element, a member carried by said element and movable relatively thereto, a locking member for engaging said first member and permitting limited movement of said element, said first member being so constructed and disposed to receive an inserted coin and by such limited movement to transfer said coin to said locking member, and means cooperating with said coin for actuating said locking member to unlocked position.

7. In a coin-controlled apparatus, a movable element, having a coin retaining member mounted thereon for relative movement a locking member having an opening and having an engaging portion cooperating with said coin retaining member, means for causing an inserted coin to be transferred from said coin retaining member to said locking member to release said locking member to permit movement of said element, and means responsive to such movement for moving said coin to cause it to pass through said opening.

8. In a coin-controlled apparatus, a movable element, a member movable therewith and relatively movable thereto; a locking member for engaging said first mentioned member and normally spaced therefrom, whereby limited movement of said element is permitted; means responsive to such limited movement in one direction to cause an inserted coin to move one of said members to destroy the engagement between them, and means for causing return movement when said coin fails to destroy such engagement to move said coin through the space between said members.

9. A coin-controlled apparatus having, in

- combination, a movable element formed for receiving a coin, a coin retaining part movable with said element and movable relative thereto into and out of coin retaining position, spaced stop members for engaging said part, said stop members permitting limited movement of said element and part and moving said part into and out of coin retaining position, the stop member which moves said part out of coin retaining position being movable into and out of engaging position with said part, and means responsive to the limited movement of said element in one direction and rendered operative by the presence of an inserted coin for moving the movable stop member out of engaging position with said part.
10. In a coin-controlled apparatus, a movable element, a member carried thereby and in sliding relation thereto, a locking member normally cooperating with the first named member and permitting a limited movement of said element, means permitting the insertion of a coin for support on said first named member, means for moving said coin to transfer it to said locking member, and means for moving said coin to move said locking member out of cooperation with said first named member.
20. 11. In a coin-controlled apparatus, a movable element, a member carried thereby and in sliding relation thereto, a pivoted locking member normally cooperating with the first named member and permitting a limited movement of said element, means permitting the insertion of a coin for support on said first named member, means for moving said coin to transfer it to said locking member, and means for moving said coin to move said locking member out of cooperation with said first named member.
25. 12. In a coin-controlled apparatus, a rotatable element, a member slidably supported by said member, a pivoted lever having a part in the path of the first named member and normally spaced therefrom, means permitting the insertion of a coin for support on said first named member, means for moving said coin when said element is rotated to transfer it to said lever, and a cam cooperating with said coin when on said lever for moving the latter out of the path of said first named member.
30. 13. A coin-controlled apparatus having, in combination, a movable element, locking means for said element comprising a part movable therewith and a locking dog normally spaced from said part, a coin slot in said element normally closed by said part, a coin chute for guiding coins into said slot, and magnetic means for deflecting slugs of magnetic material from said chute into the space between said part and said dog.
35. 14. A coin-controlled apparatus having, in combination, a movable element, locking means for said element comprising a part movable therewith and a locking dog normally spaced from said part, a coin slot in said element normally closed by said part, a coin chute for guiding coins into said slot, magnetic means for deflecting slugs of magnetic material from said chute into the space between said part and said dog, and slug exposing means comprising a chute beneath said space.

In testimony whereof, I have signed my name to this specification.

CHARLES LEA.
